Primary Examiner—Bernarr E. Gregory**[57] ABSTRACT**

Most power supply regulators either cause the output

voltage to drop-off gradually, or caused output oscillation upon reaching or exceeding the limit current. Current limit feedback to an error amplifier within a switching regulator is used to control the output voltage, prevent oscillation, insure that current limiting does not occur until a well-defined threshold is achieved and then steeply limit the current. The circuit uses feedback to the switching regulator to maintain the output voltage within desired limits. The output current flows through the current limit resistor R_c thus providing a voltage proportional to the current at the base-emitter junction of Q_1 via CR_1 and R_2 . During normal operation, the forward biased CR_1 voltage maintains a reverse bias on the B-E junction of Q_1 . When the voltage across R_c exceeds the forward bias on CR_1 , Q_1 turns on, hence turning on Q_2 , thus providing its contribution to the current limit feedback circuitry for use by the switching regulator.

1 Claim, 1 Drawing Sheet

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.

FIG._1

CURRENT LIMIT CIRCUIT FOR POWER SUPPLY REGULATORS

FIELD OF THE INVENTION

This invention pertains to a method and apparatus for limiting current in a power supply.

BACKGROUND OF THE INVENTION

Most prior art circuits either caused the output voltage to drop-off gradually, or caused output oscillation upon reaching or exceeding the limit current.

OBJECTIVES OF THE INVENTION

It is therefore a primary objective of the present invention to provide a circuit for regulating voltage of a power supply to provide good regulation of voltage up to a desired current limit value.

It is another objective to drop the voltage sharply above the desired current limit.

Still another objective is to avoid oscillation of the output voltage.

A further objective is provide a highly reliable circuit.

SUMMARY OF THE INVENTION

Current limit feedback to an error amplifier within a switching regulator is used to control the output current, prevent oscillation, insure that current limiting does not occur until a well-defined threshold is achieved and then steeply limit the current.

These objects of the invention and other objects, features and advantages to become apparent as the specification progresses are accomplished by the invention according to which, briefly stated, current limit feedback to an error amplifier within a switching regulator is used to control the output voltage and prevent oscillation.

LIST OF ADVANTAGES OF THE INVENTION

An important advantage of the present invention is that the circuit uses provides a square voltage-current curve.

Another advantage is that the circuit uses few components.

A further advantage is that most components of the circuit are fairly insensitive to component tolerances or parameters.

Still another advantage is that oscillation is prevented.

These and further objectives, constructional and operational characteristics, and advantages of the invention will no doubt be more evident to those skilled in the art from the detailed description given hereinafter with reference to the figures of the accompanying drawings which illustrate a preferred embodiment by way of non-limiting example.

BRIEF DESCRIPTION OF THE DRAWINGS

FIG. 1 shows the circuit according to the invention.

GLOSSARY

The following is a glossary of circuit elements as referenced and employed in the present invention.

5	Q_1 —2N2222A transistor
	Q_2 —2N2907A transistor
	Q_3 —2N3584 transistor
	Q_4 —2N3584 transistor
	CR_1, CR_2 —1N414B diodes
10	R_c —0.249 Ω resistor
	R_1 —1000 Ω resistor
	R_2 —16.2 Ω resistor
	R_3 —4.99 Ω resistor
	R_4 —499 Ω resistor
	R_5 —3.01k Ω resistor
	R_6 —499 Ω resistor
	R_7 —90.9 Ω resistor
	R_8 —10k Ω resistor
	C_1, C_2 —0.01 mfd capacitors
	SR—switching regulator IC, e.g. Harris FG1532

DESCRIPTION OF THE PREFERRED EMBODIMENTS

Referring now to the drawings wherein like reference numerals are used to designate like or corresponding parts throughout the various figures thereof, there is shown in FIG. 1 the circuit according to the invention.

The invention uses feedback to the switching regulator to maintain the output voltage V_{out} within desired limits. The output current flows through the current limit resistor R_c thus providing a voltage proportional to the current at the base-emitter junction of Q_1 via CR_1 and R_2 . During normal operation, the forward biased CR_1 voltage maintains a reverse bias on the B-E junction of Q_1 . When the voltage across R_c exceeds the forward bias on CR_1 , Q_1 turns on, hence turning on Q_2 , thus providing its contribution to the current limit feedback circuitry for use by the switching regulator SR.

R_1 is a resistor that maintains the continuous forward bias current through CR_1 . R_2 provides some current limiting for the base-emitter junction of Q_1 during hard current limiting conditions and output current spikes. R_3 prevents Q_2 from being driven too hard by Q_1 . R_4 provides a path for leakage current from the base-collector junction of Q_2 thus helping to hold it off during normal operation. Capacitor C_1 is simply a filter capacitor for the regulator output.

Within the feedback circuit, R_5 and R_6 scale the feedback signal to the power control circuit. C_2 and CR_2 are filters to reduce the noise to the power control circuit.

This invention is not limited to the preferred embodiment and alternatives heretofore described, to which variations and improvements may be made, without departing from the scope of protection of the present patent and true spirit of the invention, the characteristics of which are summarized in the following claims.

What is claimed is:

1. A circuit for regulating voltage in a power supply, comprising:
  - a power control circuit means for controlling a voltage of a power source,
  - a current limiting means for generating a feedback signal to said power control circuit means while limiting current to an output, and
  - a feedback circuit means for scaling a signal from a signal generation means to be sent to said power control circuit means.
